Oliver O'Brien

Attorney

UNITED STATES PATENT OFFICE.

WERNER SENN, OF NEW YORK, N. Y.

WATCH.

Application filed July 7, 1923. Serial No. 650,023.

To all whom it may concern:

Be it known that I, WERNER SENN, a citizen of the Republic of Switzerland, residing at New York city, in the county of 5 New York and State of New York, have invented certain new and useful Improvements in Watches, of which the following is a specification.

This invention relates to the art of 10 horology, and has particular reference to the provision of novel and improved means for the setting of the hands of watches and the winding of the mainspring thereof.

In conventional forms of wrist watches, 15 considerable difficulty and inconvenience is experienced in manipulating the well-known stem set and stem winding devices, and it is accordingly an object of this invention to provide a more desirable means for accomplishing these functions.

Another object of the invention is to provide hand setting and spring winding devices for watches which embody the desired qualities of durability and simplicity of 20 construction.

With the above general objects in view, and others that will become apparent as the nature of the invention is better understood, the same consists in the novel form, 25 combination and arrangement of parts hereinafter more fully described, shown in the accompanying drawings and claimed.

In the drawings, wherein like reference characters indicate corresponding parts 30 throughout the views,

The figure is a somewhat diagrammatic view, partly in plan and partly in section, illustrating spring winding and hand setting devices constructed in accordance with 35 the present invention.

In the drawings, 5 indicates the watch case which is preferably of arcuate form in section, 6 indicates the spring barrel of the mainspring of the watch, and 7 denotes the 40 spring shaft thereof. In accordance with the present invention, the watch case 5 is provided with a circumferentially extending elongated slot 8 at one side thereof and a slide block 9 is disposed against and fits 45 the internal face of the case 5, as shown in Figure 1. An arcuate slide 10 is disposed against the outer surface of the case 5 and connected with the block 9 by any suitable means, such as a bolt or screw 11, which 50 extends through the slot 8. This arcuate slide piece 10 has a reduced portion 12 slid-

ably disposed in the slot 8 and into which the bolt or screw 11 is threaded, whereby the members 9 and 10 are effectively connected and held into engagement with the faces of the watch case. For convenience in sliding the member 10, the latter is provided with a raised finger portion 12¹, preferably disposed centrally of its length as shown. A bell crank lever 13 is pivoted to the frame of the watch as at 14, and one arm of the same is extended in an elongated opening 15 of the slide 9 so that when this block is moved, the bell crank lever 13 is rocked. The opposite ends of the opening 15 are beveled as seen. The other arm of the bell crank lever 13 is provided with a segment gear 16, and a spur gear 17 is mounted upon the shaft 7 of the spring barrel so as to mesh with the segment gear 16 as shown. The 60 mounting of the gear 17 includes a ratchet mechanism generally denoted by the numeral 18, by means of which the shaft 7 will be rotated when the gear 17 is moved in one direction, but which permits free movement of the gear 17 in the reverse direction without turning or influencing the shaft 7. In view of this construction, it will be seen that mere reciprocation of the actuating slide 10 will result in effective and easy winding of the mainspring, which is retained in wound position by the usual pawl and ratchet mechanism.

The hand setting mechanism embodies the usual gear 22 of the shaft carrying the hands 23 and meshing with another gear 24 disposed beside the gear 22. In accordance with the present invention an arm 25 is pivoted at one end, as at 26, to the frame of the watch for swinging movement 90 toward and away from the gear 24, and this arm has a gear 27 rotatably mounted thereon as at 28 in position to move toward and away from the gear 24 for meshing therewith or disengaging therefrom. This gear 27 is normally held in an outward position out of mesh with the gear 24 by means of a resilient spring 29 fixed at one end to the frame of the watch, as at 30, and having its other end disposed in engagement with the upturned free end portion 31 of the arm 25. This side of the watch case is provided with a circumferentially extending elongated slot 32, and a segmental rack bar 33 is disposed adjacent this slot against the inner surface of the watch case. The teeth of the rack bar 33 are in mesh with the teeth 95 100 105 110

of the gear 27 as shown, so that reciprocation of the rack bar will cause rotation of the gear 27.

An arcuate operating slide 34 is disposed against the outer surface of the case 5 and connected with the rack bar 33 by means of screws 35 or the like, whereby said rack bar is held in place to a certain extent, as the heads of the screws 35 are positioned in sockets 36 in the outer surface of the rack bar 33 and extend through the slot 32 as well as being threaded into the slide 34. The central portion of the rack bar 33 is provided with a threaded socket into which is screwed a stem 37 which has a button or fingerpiece 38 fixed upon the outer end thereof, which button is movable radially in the slide 34 for forcing the stem 37 inwardly and correspondingly moving the rack bar 33 and gear 27 so as to mesh the gear 27 with the gear 24 when desired to set the hands. As shown, the stem 37 is of sufficient length so as to normally position the inner end of the finger piece 38 in spaced relation to the outer surface of the watch case 5, and the operating slide 34 is provided with a socket as at 39 in which the finger-piece 38 is radially movable. From the above description it will be seen that the gear 27 is normally out of mesh with the gear 24 so as to permit free movement of the hands 23 in the usual manner under the influence of the mainspring through the usual gearing, not shown. If it is desired to set the hands, the user simply presses inwardly on the button 38 so as to move the rack bar 33 inwardly, thereby causing movement of the gear 27 inwardly into engagement with the gear 24. The operating slide 34 is then moved in one direction so as to cause the gear 27 to be rotated and its rotation is imparted to the gear 24 for rotating the hands. The pres-

sure on the finger piece or knob 38 is then released so as to allow the gear 27 to disengage from the gear 24, whereupon the slide 34 may be returned to the other end of the slot. By repeating the above operation of the slide 34, the hands will be moved to the required extent for properly setting the same.

From the foregoing description, it is believed that the construction and operation as well as the advantages of the present invention will be readily understood and appreciated by those skilled in the art, it being noted that the slide pieces 10 and 34 are made of sufficient length as to cover the slots 8 and 32 in all positions of the same, thus excluding dust and dirt from the watch movement.

Minor changes may be made without departing from the spirit and scope of the invention as claimed.

Having thus described my invention, what I claim as new and desire to secure by Letters Patent is:

In a watch having a main spring barrel provided with a winding shaft, a gear having a ratchet connection with said shaft, a bell crank lever pivoted in the watch casing and having a segmental gear upon one end in mesh with the teeth of said gear; a slide, said watch including a casing of arcuate form provided with a circumferentially extending elongated slot with which said slide cooperates, said slide having an elongated opening adapted to register with said slot and the opposite end of said opening being beveled, the adjacent arm of the aforesaid bell crank lever being disposed in said opening, and means upon the exterior of the watch for reciprocating said slide.

In testimony whereof I affix my signature.

WERNER SENN.
